UNITED STATES PATENT OFFICE.

RONELLO F. PRATT, OF EVERETT, MASSACHUSETTS.

SHUTTER-WORKER.

SPECIFICATION forming part of Letters Patent No. 292,354, dated January 22, 1884.

Application filed August 31, 1883. (No model.)

To all whom it may concern:

Be it known that I, RONELLO F. PRATT, a citizen of the United States, residing at Everett, in the county of Middlesex and State of Massachusetts, have invented certain new and useful Improvements in Devices for Operating Blinds or Shutters, of which the following is a specification.

My invention relates to a new and improved device by which the outside blinds and shutters can be opened and closed and also fastened from the inside without opening the window.

The invention consists of a rod or spindle which passes through a tube or sleeve, the two passing through a hole in the wall or frame, just below the window-sill. The inner ends of the sleeve and spindle are each provided with a handle, by which either can be rotated independently of the other. On the outer end of both the spindle and the sleeve is a toothed segment, which gear respectively with a rack on a rod or bar, having a rack at its opposite end which gears with a pinion secured to the window-sill. To this pinion is connected an arm or rod, which is attached or pivoted to the lower part of the blind. By turning the handles and the spindle and sleeve on the inside, either or both blinds can be opened or closed, as desired. A clamping device is also provided on the inside, by which the blinds can be secured in any desired position, either fully or partially closed or opened.

Referring to the accompanying drawings, Figure 1 is an outside view of a portion of a window and blinds with my invention applied. Fig. 2 is a section on the line *x x* of Fig. 1. Fig. 3 is a vertical section on the line *y y* of Fig. 2; and Fig. 4 is a section, somewhat enlarged, on the line *z z* of Fig. 2.

A is the window-frame, *B* the window-sill, and *C C* are the blinds, all of the usual construction.

Through the wall *O* of the building, under the center of the window-sill, is a hole, through which passes a tube or sleeve, *D*, set in proper bearings, so as to rotate freely, and passing through the sleeve *D* is a rod or spindle, *E*.

On the inner end of the sleeve *D*, within the room, is fitted a handle, *D'*, by which the sleeve *D* is turned in either direction, and on the end of the spindle *E* is also a handle, *E'*, for turning the said spindle.

To the handle *E'* is attached a slotted plate, *e*, and to the handle *D'* is attached a screw, *d*, which passes through the slot in plate *e*, and on the screw *d* is a thumb-nut, *a*, by means of which the handles *D' E'* can be locked in any desired position.

On the outer end of the sleeve *D*, outside the window, is secured a quadrantal toothed segment, *G*, and on the end of the spindle *E* is a similar toothed segment, *F*.

H and *I* are bars, which slide in opposite directions on a line parallel with the window-sill, and are provided with teeth on the underside of their inner ends, which engage with the toothed segments *F G*, respectively. The bars *H I*, extending toward the ends of the sill, are bent upward, as shown in Fig. 1, and inward horizontally, as shown in Fig. 2, and are provided with teeth at their outer ends, which engage with pinions *J K*. The said pinions are pivoted to the window-sill, and have arms *L L* attached to or forming a part of them, which arms have holes at their outer ends fitting on pins *l l* on the bottom of the blinds. Caps or covers *M* are placed over the gears *F G* to protect the latter from snow and ice, and also serve to keep the gears in position. A plate, *i*, is secured to the window-sill, and is turned up at the back, so as to hold the racks in gear with the pinions. On the outside of the wall is a sliding collar, *h*, surrounding the sleeve *D*, and held in position by a set-screw for the purpose of adjusting the device to walls of different thicknesses.

Instead of attaching the screw *d* to one of the handles *D'*, as shown, it may be inserted in the wall or the finish under the window, and the handles be secured by a thumb-screw.

When the blinds are required to be removed, they have simply to be lifted off their hinges, as they are not attached to any part of the device, the only connection being the pin at the bottom passing through the arm *L*.

It will be seen that by simply turning the handles *D' E'* the segmental gears will cause the bars *H I* to turn the pinions *J K*, thus actuating the bars *L L* to open or close the blinds or hold them in any position, as desired.

What I claim as my invention is—

1. A device for operating outside blinds or shutters from the inside of a room, the same consisting of a sleeve and inclosed spindle passing through the wall or frame of a house, said

sleeve and spindle being each provided with a toothed segment at their outer ends, in combination with two separate toothed bars, each operating a pinion and bar in connection with 5 the blinds, whereby one or both blinds may be separately operated, as desired, substantially as set forth.

2. The combination, with the handles D' E', of the locking device consisting of the slotted

plate c, the screw d, and thumb-nut a, substantially as and for the purpose set forth.

In testimony whereof I have signed my name to this specification in the presence of two subscribing witnesses.

RONELLO F. PRATT.
